UNITED STATES PATENT OFFICE.

PETER FRANTZ, OF STERLING, ILLINOIS, ASSIGNOR TO LAWRENCE C. THORNE, OF STERLING, ILLINOIS.

UMBRELLA-STICK.

1,185,650.

Specification of Letters Patent.

Patented June 6, 1916.

Application filed January 19, 1915. Serial No. 3,026.

To all whom it may concern:

Be it known that I, PETER FRANTZ, a citizen of the United States of America, and resident of Sterling, Whiteside county, Illinois (residential address 309 Ninth avenue), have invented a certain new and useful Improvement in Umbrella-Sticks, of which the following is a specification.

My invention relates to umbrellas of that kind in which the stick is composed of telescoping sections. Umbrella sticks of this kind are employed in various ways, sometimes in combination with telescoping ribs, and in some cases with ribs of the ordinary form. In any event, however, the telescoping of the stick serves to shorten the umbrella. This is done in order that the umbrella may be carried in a suit case or satchel, or for some similar purpose.

The object of my invention is to provide a telescoping stick having a strong and simple construction, and having such a construction that the upper section of the stick may be telescoped within the handle of the stick, and the tip-section within the handle-section, whereby the stick may be reduced to minimum length in a satisfactory and convenient manner without removing the handle and tip thereof.

It is also an object to provide certain details and features of construction and combinations tending to increase the general efficiency of a telescoping umbrella stick of this particular character, and which will tend to render the same more satisfactory and desirable than heretofore.

To these and other useful ends my invention consists in matters hereinafter set forth and claimed.

In the accompanying drawings—Figure 1 is a longitudinal section of an umbrella stick embodying the principles of my invention, showing the same in extended condition. Fig. 2 is a similar view, but on a larger scale, and showing the stick in telescoped condition. Fig. 3 is an enlarged cross section on line 3—3 in Fig. 2. Fig. 4 is an enlarged cross section on line 4—4 in Fig. 2. Fig. 5 is an enlarged section on line 5—5 in Fig. 2. Fig. 6 is a similar section on line 6—6 in Fig. 2.

As thus illustrated, my invention comprises a handle section A provided with a handle a , a tip section B, an upper section C, and a top notch D on the upper section, the

runner or lower notch E being arranged to slide up and down on the handle and upper sections. The said handle section is tubular from the handle thereof to a point substantially opposite the lower end of the upper section, and from this point upward the three sections are all hexagonal in character, whereby one section cannot rotate in the other. Means of any suitable kind are provided on the lower ends of the tip and upper sections to limit their upward movement when the stick is extended. The tip section is provided with a spring latch or catch b which engages the upper end of the upper section to hold the two sections in extended condition. The upper section is provided with a spring catch c which engages the upper end of the handle section to hold these two sections in extended condition. It will be understood that the catches b and c can be pressed inward to unlock the sections when it is desired to telescope the stick. When entirely telescoped, the section C moves downward to such an extent that the lower end thereof is well within the handle a on the lower end of the stick. The tip section B has a tip b^1 which limits its downward movement within the upper section. As shown, the top notch D comprises a collar d fixed on the upper end of the upper section and provided with notches for the ribs of the umbrella. Said collar has a recess d^1 which receives and telescopes over the upper end of the handle section C when the sections are telescoped. In this way said top notch serves as a stop for the end of the handle section.

The runner E is provided with a spring catch e which operates through an opening e^1 in the side of the runner, and which is adapted to engage an opening e^2 in the side of the handle section A when the runner is moved downward to lower the umbrella. In this way the runner is locked in its lowermost position, when the umbrella is lowered. The spring catch e is tensioned to move away from said opening e^1 , when the sleeve e^3 which surrounds the runner is moved upward. When the said sleeve e^3 is moved downward, as in lowering the umbrella, the spring catch e is thereby given a tension which causes it to enter the opening e^2 as soon as this point is reached. Thus the interior of the handle section is entirely free from spring catches, the spring catch for

holding the runner in lowered position being on the runner itself instead of in the handle section of the stick. Consequently, as previously explained, the upper section 5 C is free to move downward until its lower end is inside of the handle, inasmuch as the handle section has a perfectly free and unobstructed bore.

To lock the runner in raised position, the 10 upper section is provided with a spring catch F which is inclosed therein near the upper end thereof and arranged to work through a slot f in one side of the stick. This spring catch has a notch f¹ and a cam portion f², it being observed that the portion e⁴ of the runner enters said notch to hold the umbrella in raised position. At such 15 time the cam portion f² projects through the slot e⁵ in the side of the runner, and the portion e⁶ of said runner engages the notch f² of the catch F, whereby the sleeve e³ of the runner is held in raised position thereon. When it is desired to lower the umbrella, the operator grasps the sleeve e³ and pulls 20 it downward, thereby causing the portion e⁶ to engage the cam f² and thus force the catch F inward and out of engagement with the runner. As the runner is pulled downward the sleeve e³ retains the spring catch 25 e under tension and in such condition that it drops into the opening e² as soon as the runner reaches the limit of its downward movement. To raise the umbrella, the operator grasps the sleeve e³ and moves it upward, thus releasing the catch e from the 30 opening e², and thereby allowing the runner to slide upward.

To telescope the stick, all that is necessary is to simply press the catches b and c inward, thus releasing the sections and allowing them to telescope one within the other as shown in Fig. 2. If telescoping ribs d² are employed, of any suitable character, then the runner E will occupy approximately 35 the position shown in Fig. 2 when the umbrella is entirely folded or collapsed. Any well known rib construction can be used for thus positioning the runner on the handle section, and against the handle, when 40 the stick is telescoped. Thus the handle provides a shoulder for the runner to move the latter toward the top notch in collapsing and folding the umbrella. The said runner has its upper end provided with notches for 45 the braces G which may also be of any suitable known or approved character. To extend the stick the operator simply grasps the handle a in one hand and the tip b¹ in the other hand and pulls the sections into 50 their extended positions to cause the stick to assume the length necessary for use.

From the foregoing, it will be seen that the stick is reduced to minimum length without removal of either the handle or the 55 tip thereof, the upper section C of the stick

telescoping within the handle, and the tip-section B telescoping within the upper end portion of the handle-section, as well as within the upper end portion of the said upper section C, the various spring catches, 70 more especially the spring catch F and the spring catch e, being provided as arranged and shown and described to permit this telescoping of the upper section and tip-section entirely within the handle-section. And, 75 in addition, as previously explained, the top-notch D telescopes over the upper end of the handle-section, in the manner shown and described, thereby not only gaining something in the reduction of the length of 80 the stick, but also strengthening the upper end of the umbrella when entirely telescoped and folded. Furthermore, the sleeve e³ serves as a handle for raising and lowering the umbrella, and serves also to operate the 85 spring catch F by a downward pull on the runner, as well as for releasing the catch e by pushing the runner upward, thus making the release of the runner entirely automatic in both the upper and intermediate 90 positions thereof, the said runner having its lowest position located some distance below the said intermediate position. Thus, also, the umbrella can be very much shortened by simply telescoping the stick enough to bring 95 the runner down against the handle, and to bring the tip-section entirely within the upper section. And, when thus partially shortened, the ribs will not be telescoped and the handle-section will not have its upper end 100 disposed within the top-notch to which the ribs are attached. But, in any event, when the stick is entirely telescoped, both the upper section and the tip-section thereof are 105 entirely within the handle-section, and the said upper section is partially within the handle, thus reducing the stick in minimum length without removal of any of the parts thereof.

The catch f⁴ on the locking device F serves, it will be understood, to limit the upward movement of the runner on the stick. The flange or rib e⁷ on the lower end of said runner engages the lower end of the sleeve e³ to limit the downward motion of 110 the latter. Furthermore, the top-notch D, by engaging both the upper end of the handle-section A and the tip b¹, as shown in Fig. 2, serves to limit the entire telescoping operation, so that the lower end of the tip-section does not engage anything, and so that the lower end of the upper section C does not engage anything, the said top-notch D serving as a stop to limit the entire 115 operation.

What I claim as my invention is:—

1. An umbrella comprising a stick, a runner on said stick, a spring catch on said runner, means on the lower portion of said stick to engage said catch, a spring locking 120

device in the upper portion of said stick, means on said runner to engage said device, a sliding sleeve covering the catch on said runner, means on said sleeve to operate said 5 catch, a cam on said device, and means on said sleeve to engage said cam.

2. An umbrella comprising a stick, a runner on said stick, a spring catch on said runner, means on the lower portion of said stick 10 to engage said catch, a spring locking device in the upper portion of said stick, means on said runner to engage said device, a sliding sleeve covering the catch on said runner, means on said sleeve to operate said 15 catch, a cam on said device, and means on said sleeve to engage said cam, said stick having telescoping sections, and means on the end of one section to engage said cam.

3. An umbrella comprising a stick, a runner on said stick, a spring catch on said runner, means on the lower portion of said stick to engage said catch, a spring locking device in the upper portion of said stick, means on said runner to engage said device, 20 a sliding sleeve covering the catch on said runner, means on said sleeve to operate said catch, a cam on said device, and means on said sleeve to engage said cam, said device having means to limit the upward motion 25 of said runner, and said runner having means at its lower end to limit the downward motion of said sleeve thereon.

4. An umbrella stick comprising a tubular handle-section, a tubular tip-section, a 35 tubular upper section directly engaging both the handle-section and the tip-section, all three sections telescoping together to reduce the stick to minimum length without removal of the handle and tip thereof, 40 and to bring practically the entire length of the tip-section and the upper section within the handle-section, a top-notch fixed on the upper end of the upper section to slide upward on the tip-section, a runner to slide on the handle-section and the upper section, said runner having 45 upper and lower and intermediate positions on the stick, being in said lower position when the handle-section is telescoped in direct contact with the upper section over the tip-section, a spring catch carried on the runner to hold it in intermediate position and permit telescoping of the upper section 50 within the handle, upper and lower spring catches in the stick to hold the sections in 55 extended position, and an intermediate spring catch arranged to hold said runner in said upper position thereof, said intermediate spring catch being disposed a fixed distance below said top-notch to permit full 60 telescoping of the tip-section and said upper catch within said handle-section, the end of said upper section engaging said head to limit the telescoping of the tip-section, the top-notch engaging the end of the 65 handle-section to limit the telescoping of the upper section, said top-notch thereby serving to limit the entire telescoping operation.

tion within the handle, upper and lower spring catches in the stick to hold the sections in extended position, and an intermediate spring catch arranged to hold said runner in said upper position thereof, said intermediate spring catch being disposed a fixed distance below said top-notch to permit full telescoping of the tip-section and said upper catch within said handle-section.

5. An umbrella stick comprising a tubular handle-section, a tubular tip-section, a tubular upper section directly engaging both the handle-section and the tip-section, all three sections telescoping together to reduce the stick to minimum length without removal of the handle and tip thereof, and to bring practically the entire length of the tip-section and the upper section within the handle-section, a head on said tip-section, a top-notch fixed on the upper end of the upper section to slide upward on the tip-section, a runner to slide on the handle-section and the upper section, said runner having upper and lower and intermediate positions on the stick, being in said lower position when the handle-section is telescoped in direct contact with the upper section over the tip-section, a spring catch carried on the runner to hold it in intermediate position and permit telescoping of the upper section within the handle, upper and lower spring catches in the stick to hold the sections in 80 extended position, and an intermediate spring catch arranged to hold said runner in said upper position thereof, said intermediate spring catch being disposed a fixed distance below said top-notch to permit full 85 telescoping of the tip-section and said upper catch within said handle-section, the end of said upper section engaging said head to limit the telescoping of the tip-section, the top-notch engaging the end of the 90 handle-section to limit the telescoping of the upper section, said top-notch thereby serving to limit the entire telescoping operation.

Signed by me at Sterling, Illinois, this 100
9th day of January, 1915.
